UNITED STATES PATENT OFFICE

GEORGE L. MOREHEAD AND CHARLES M. YOUNG, JR., OF PHILADELPHIA, PENNSYLVANIA, ASSIGNORS TO LINK-BELT COMPANY, OF CHICAGO, ILLINOIS, A CORPORATION OF ILLINOIS

TROLLEY BUCKET

Application filed April 27, 1931. Serial No. 533,046.

This invention relates to a hoisting and conveying means. In one form it is shown as applied to a trolley bucket, although it is not limited to use in that connection.

5 One object of the invention is to provide a bucket having a bottom opening closed by one or more doors, so arranged that upon tilting of the bucket these doors automatically close.

10 Another object of the invention is to provide means for guiding such a bucket as it changes its direction of movement from that along the trolley to that of the loading position.

15 Another object is to provide a shock absorbing or alleviating means in connection with such a bucket, which shock absorbing means utilizes an essential part of the apparatus and so avoids the use of additional parts.

20 Other objects will appear from time to time in the specification and claims.

The invention is illustrated more or less diagrammatically in the accompanying drawings, wherein:—

Figure 1 is an end elevation of a bucket, showing it in position supported from a trolley, the trolley track being in section;

Figure 2 is a side elevation of the bucket, showing it in position supported by the trolley;

Figure 3 is a diagrammatic vertical cross section, showing the bucket and loader and associated parts;

Figure 4 is a diagrammatic plan view, showing the bucket centralizing means;

Figure 5 is a side elevation, showing the same bucket centralizing means;

Figure 6 is a perspective view of a modified form of door and door locking mechanism;

Figure 7 is a perspective view of a further modified form of door and door locking mechanism; and

Figure 8 is a transverse vertical section of the construction shown in Figure 7.

Like parts are designated by like characters throughout the specification and drawings.

50 A is a rail or track adapted to support a

trolley. The track is itself supported by any suitable means. A trolley frame made up preferably of two channel frame members A¹ A¹ is used. Hangers A² extend upwardly from the trolley frame and pivotally support 55 a yoke member A³. Each of the yoke members has one branch A⁴ A⁴ positioned upon one side of the track A and wheels A⁵ are journaled upon the members A⁴. The wheels are flanged as shown and rest upon the flange 60 of the track member A. Suitable lubricating and adjusting parts are used with the construction just described. Their details form no particular part of the present invention and will not be described in detail. A⁶, A⁶ 65 are hoisting rope sheaves journaled in the trolley frame and preferably between the channel members A¹. A⁷ A⁷ are preferably squared loosely mounted shank members which are mounted for limited vertical 70 reciprocation in the trolley frame, preferably between the frame members A¹ and held against rotation by the fact that they are squared. Each of the members A⁷ at its lower end carries an extended contact plate A⁸ and at its upper end has journaled in it a sheave 75 or flanged wheel A⁹, the member A⁷ being bifurcated at its upper end as indicated particularly in Figure 1, to receive the sheave. A hoisting rope A¹⁰ is fastened at each end 80 to the trolley frame and may be engaged about a bar A¹¹. A¹² is a hoisting rope which is in contact with the shock absorber sheaves A⁹ and with the sheaves A⁶ and a sheave upon the bucket, as will be described below.

85 A bucket which may be of any suitable shape but in the present form of the invention is of generally rectangular cross section, is formed of end members or plates B and side members B¹ and B². The bottom of the bucket is partially open and partially closed. A V-shaped member B³ is positioned adjacent the bottom of the bucket and partially closes it, as shown particularly in Figure 1, with its sharp edge pointed upward. The end plates B may be of irregular shape, indicated in Figure 1, cut away at the bottom as shown in that figure. The side plate B² extends from the bottom to the top of the bucket and is inclined 90 inwardly. The side plate B¹ extends substan- 95 100

tially vertically from the bottom of the bucket to a point short of the top, terminating at B^4 , as indicated in Figures 1 and 2. Adjacent the top of the bucket on the side of the plate B^1 is a loader operating bar B^5 . It may be supported in brackets B^6 fastened to the ends plates B . On the side plate B^2 two axles or shafts B^7 B^7 are positioned. They carry flanged rollers B^8 B^8 shaped to engage the tracks. Positioned at the upper end of the bucket and fastened preferably to the side plates B are bearing and contact bracket members B^9 . Each of them terminates in or carries on its upper surface laterally extended portion B^{10} . B^{11} is a bail which may be formed in any suitable manner but is ordinarily formed of one or more channel members joined together. This bail is provided in its end with trunnions B^{12} which are journaled in the bearing supporting members B^9 . Supported from the bail B^{11} is a hoisting sheave B^{13} which is journaled in suitable bearings formed in the members B^{14} . B^{15} , B^{15} are cable guides situated adjacent the sheave B^{13} , serving to guide the cable to and from it.

In the bottom of the bucket, in the form shown in Figures 1 and 2, two doors or gates are pivoted. The door C is pivoted at C^1 and is preferably relatively large and heavy. It has attached to it a lever extension C^2 . A relatively smaller and lighter door C^3 is pivotally mounted at C^4 and has fastened to it a lever extension C^5 . A link C^6 connects the members C^2 and C^5 . These links and lever connections may be provided on only one end of the doors or on both ends. C^7 is a toggle arm or link pivoted at one end upon the door C^3 and fastened at its other end to a second toggle arm C^8 which at its opposite end is pivoted to the door C . The toggle C^8 may be made heavy or may be provided with a counter-weight or weighted portion C^9 . The lever extension C^6 may be provided with sufficient weight, either by being made heavy itself or by having attached to it a counter-weight so that it balances the door C^3 . The doors C and C^3 are provided with suitable frame and lip members, as shown in the figures. The bottom of the bucket may also be provided with suitable lip members, as shown particularly in Figure 1.

The bucket is intended to be moved into position with relation to a loader so that it may receive material from the latter. As shown in Figure 3, D is a pit into which a bin D^1 extends. From the bin a loader D^2 is adapted to discharge material through a spout D^3 into the bucket. Inclined tracks D^4 extend into and up out of the pit D . These tracks are adapted to receive the flanged wheels B^8 of the bucket and so to support and guide the bucket in its movement to, into and from the pit. The tracks D^4 terminate at or near an inclined surface member D^5 . Ad-

jacent the upper ends of the tracks D^4 is a V-shaped formation preferably made up of a pair of rails D^6 . As the bucket descends from the dotted line position X of Figure 5, to the full line position of Figure 5, the rollers or wheels B^8 contact first the inclined surface member D^6 and then by means of the centralizing members D^7 , these wheels are guided into proper engagement with the tracks D^4 and thus the bucket is guided onto the tracks so that it can move along them into position in the pit for loading. 70 75

As shown in Figure 6, the bucket and door construction is the same as that described above and shown particularly in Figures 1 and 2. A different toggle construction is used, however, and the toggle is applied only to the lighter door C^3 . At its other end the toggle is fastened to a fixed support. 80

E is a support fastened to the door C^3 to which one toggle arm E^1 is mounted. E^2 is a fixed support on the V-shaped member B^3 in the bucket bottom. A second toggle arm E^3 is pivoted at one end on the support E^2 and at its other end as at E^4 is pivoted to the toggle arm E^1 . The toggle arm E^3 may have formed upon it one or more laterally extended and weighted parts E^5 . These parts serve to weight the toggle and also, if laterally extended as shown in Figure 6, they serve as contact members when the bucket is lowered for emptying. 90 95

In the further modification shown in Figures 7 and 8, two doors are used, but they are hung so as to swing outwardly in opening, as indicated in the dotted line position of Figure 8, rather than swinging inwardly for opening, as indicated in the full line position of Figure 1. Thus, as shown in Figures 7 and 8, F is a relatively large and heavy door, hinged to the body as at F^1 and provided with an extension F^2 . F^3 is a relatively lighter and smaller door, hinged to the body as at F^4 and provided with an extension F^5 . A link F^6 joins the extensions F^2 and F^5 . The doors may be provided with suitable stiffening frame members or lip members, as shown in the figures. In this form of the invention, there is no toggle. The door F is perforated as at F^7 and a single latch projects through it and in one position engages it to hold the door closed. 100 110 115

A fixed support G is provided upon the V-shaped member B^3 in the bottom of the bucket. Pivoted upon this fixed support is a latch having one branch or arm G^1 terminating in a hook portion G^2 which may extend through the perforation F^7 in the door F and in one position engage the door to hold it closed. The latch has a second arm G^3 which may carry a weighted and laterally extended portion G^4 and preferably intermediate its ends has a hooking nose or part G^5 which is adapted to engage the edge of the door F^3 to hold it locked. The parts are 120 125 130

shown in the closed position in full lines in Figure 8 and in the open position in the dotted lines of that figure. For some purposes it is desirable to limit the opening movement of the door F³. For this purpose a stop may be provided. As shown, one or both of the extensions F⁵ of the door F³ is provided with an additional projection G⁶ and one or more stops G⁷ are positioned on the bucket walls, as indicated in Figure 7, and when the door moves to the open position the member or members G⁶ contact the stop or stops G⁷ and limit the movement of the door F³. The stop thus serves also, through the links F⁶, to limit the movement of the door F. This stop construction just described need not always be used.

It will be realized that whereas we have herewith shown and described a practical operative device, nevertheless many changes might be made in the size, shape, number and disposition of parts without departing from the spirit of our invention and we wish, therefore, that our showing be taken as in a sense diagrammatic. For some purposes it is not necessary to have both of the two hook portions G² and G⁵. Since the doors are linked together, if either of them is held by a hook the other is held closed. Therefore, sometimes one or the other of the hook parts G² or G⁵ may be eliminated.

The use and operation of the invention are as follows:

While the bucket of this invention might be used in many connections, it is advantageously used as a trolley bucket in connection with a trolley conveying system in which means are provided for dumping material into the bucket and for raising the bucket and conveying it along a trolley system and for dumping it. As shown in Figure 3, the loader is conveniently located in a pit into which the bucket is moved along tracks.

Assume first that the bucket has been emp-
45 tied, that the doors are in the position shown in full lines in Figure 1, and the bucket is hanging from or supported from the trolley structure. The bucket is moved along the trolley by means of the traversing rope to the right, toward the position shown in dotted lines in Figure 5. The bucket is still hanging vertically and is not in contact with the tracks and the doors are open. When the bucket reaches the position shown in dotted lines in Figure 5, it is lowered until the rollers contact the inclined surface D⁵. They engage or contact the centralizing members D⁶ and are thus guided onto the tracks D⁴. The bucket as it runs down the inclined surface D⁵ comes onto the tracks D⁴ and is tilted from a vertical position to a position at an angle to the vertical. As it reaches this position, the heavier door C swings downwardly from the open position toward the position shown in Figure 3. Through the link C⁶

which is connected to the door C and the door C³ the downward or closing movement of the door C is effective to move the door C³ upward and to close it. As this movement occurs, the toggle swings to the position shown in Figure 3, in which the toggle serves additionally to hold the doors in the closed position. The toggle is so constructed that the central joint falls sufficiently below a line drawn from the center of the end bearing of each toggle arm, so that the toggle tends to remain in the extended position and to have a locking effect.

As the bucket is lowered further into the pit beneath the loader, the member B⁵ contacts a part of the loader and moves it to an open position so that material is discharged into the open upper end of the bucket. When the bucket is loaded with material it is hoisted up the tracks and moves from the inclined position to the vertical position. The details of the loader and its method of operation are omitted as these details form no particular part of the present invention.

As the bucket is hoisted further upward, it finally leaves the tracks D⁴ and the inclined surface D⁵ entirely and comes into contact with the trolley frame. The lateral extensions B¹⁰ of the upper end of the bucket contact the extensions A⁸ on the shock absorbing shanks A⁷. Since these shanks carry sheaves A⁹ over which the hoisting rope runs, and since that rope is already under tension, as soon as the parts B¹⁰ have contacted the parts A⁸ the further upward movement of the bucket is resisted by the tension of the hoisting rope. The hoisting rope which is a flexible member and which is already under tension, thus performs the dual purpose of acting as a hoisting rope and serving as a yielding or resilient tension means in a shock absorbing construction. This construction serves as a means of leveling the bucket and as a means of reducing swinging of the bucket.

With the bucket now in position in contact with the trolley truck, the latter, with the bucket, is moved by the traversing rope to the desired point of discharge. When that point has been reached, further movement of the truck is stopped, the bucket is lowered by the hoisting rope and when the bottom of the bucket comes in contact with a more or less fixed object, such as the top of a pile of material, the toggle is broken, the doors are unlatched and as soon as free to do so, move to the open position shown in full lines in Figure 1. As soon as the bucket is in the upper position, the doors will, of their own weight, swing open when free to do so and the weight of the material within the bucket is also effective to move the doors to the open position. Since a symmetrical discharge, that is an equal discharge, from each door

is desired, the larger door C is arranged so that it does not swing as far as the smaller door C². This is evident from an inspection of Figure 1. Thus a symmetrical and equal discharge of material through both doors results and this has the advantage of forming a symmetrical pile of material so that with each succeeding trip of the bucket it contacts a symmetrical pile and any tendency of the bucket to fall down the slope of the pile before the doors are unlocked is avoided. After the bucket has contacted the pile and the doors have been opened, it is raised, the discharge of material is completed.

After completing its discharge, the bucket is further hoisted so that it again comes in contact with the trolley truck, the latter is moved back until the bucket reaches the dotted line position of Figure 5, when it is lowered as described above and again comes onto the tracks D⁴, being tilted as it does so, so that the doors close under their own weight and automatically, as the door C tends to move to the closed position when the bucket is tilted.

In Figure 6 a modified form of the construction is shown in which the doors are substantially the same as shown in the other forms. The toggle mechanism is different, however. The toggle is not fastened to both doors but is fastened only to the lighter door C³ and its other end is fastened to a fixed abutment or support E² on the V-shaped member B³ in the bottom of the bucket. The operation of this form of bucket is substantially the same as that of the other form just described. Tilting of the bucket causes the door C to swing to a closed position and through the links C⁶ this closes the other door C³ and when the doors are in the closed position the toggle moves into the extended or locking position as shown in Figure 6. Dumping of this bucket is accomplished in the same manner as that described above in connection with the other form. The bucket is lowered onto a pile of material and the portions E⁵ of the toggle strike the material and are forced upward out of the extended or locking position so that the doors are free to move to the open position, which they do under the influence of their own weight or under the influence of the weight of material within the bucket.

In the modified form shown in Figures 7 and 8 the doors, instead of being hinged or pivoted to swing inwardly, as shown in the preceding forms, are hinged to swing outwardly. In this form of the device F is the heavy door. Instead of the toggle a pivoted latch is used. The doors are connected together by links F⁶ which serve the same purpose as the links C⁶. When the bucket is tipped the door F swings downwardly to the position shown in Figure 7, and to the full line position of Figure 8. As it moves down-

wardly to the closing position, the links F⁶ cause the door F⁵ to move upwardly or to the closed position. As this occurs the latch G swings into position to engage the two doors and hold them closed, the nose G² of the latch penetrating the perforation F⁷ of the door F and the portion G⁵ of the latch engaging the edge of the door F³. The parts will be held in this position until the bucket is dumped. When that occurs, the bucket is lowered into contact with the pile of material. The extended portion G⁴ of the latch contacts the material and the latch is thus swung out of engagement with the two doors, permitting them to swing open, thus permitting discharge of the material.

We claim:

1. In combination in a bucket, having an opening in its bottom, a plurality of movable doors mounted to close said opening, said doors adapted, when free to move and when the bucket is in a vertical position, to swing open and adapted when the bucket is in an inclined position automatically to swing closed. 85

2. In combination in a bucket, having an opening in its bottom, a plurality of movable doors mounted to close said opening, said doors adapted, when free to move and when the bucket is in a vertical position, to swing open and adapted when the bucket is in an inclined position automatically to swing closed, and a latching member adapted, when said doors have moved to the closed position, to latch them in said position. 95

3. In combination in a bucket, having an opening in its bottom, a plurality of movable doors mounted to close said opening, said doors adapted, when free to move and when the bucket is in a vertical position, to swing open and adapted when the bucket is in an inclined position automatically to swing closed, and a latching member adapted automatically, when said doors have moved to the closed position, to latch them in said position. 100

4. In combination in a bucket, having an opening in its bottom, a fixed member partially closing said open bottom, and a plurality of movable doors mounted to close said opening, said doors adapted when free to move and when the bucket is in a vertical position, to swing open and adapted when the bucket is in an inclined position automatically to swing closed, and a latching member adapted automatically, when said doors have moved to the closed position, to latch them in said position. 110

5. In combination in a bucket, having an opening in its bottom, a plurality of doors mounted in said bottom, one of said doors adapted when the bucket is tilted to swing closed, and a connection between said doors to cause closing movement of one auto- 115 120 125 130

matically to close the other and means for tilting the bucket.

6. In combination in a bucket, having an opening in its bottom, a plurality of doors mounted in said bottom, one of said doors adapted when the bucket is tilted to swing closed, and a connection between said doors to cause closing movement of one automatically to close the other, and a latch adapted to move to engage a door and to hold it in the closed position and means for tilting the bucket.

7. In combination in a bucket, having an opening in its bottom, a plurality of doors mounted in said bottom, one of said doors adapted when the bucket is tilted to swing closed, and a connection between said doors to cause closing movement of one automatically to close the other, and a latch associated with one of said doors, adapted automatically to move to engage a door and to hold it in the closed position and means for tilting the bucket.

8. In combination in a bucket, having an opening in its bottom, a plurality of doors mounted in said bottom, one of said doors adapted when the bucket is tilted to swing closed, and a connection between said doors to cause closing movement of one automatically to close the other, and a latch associated with one of said doors, adapted automatically, as the door moves to the closed position, to move to engage a door and to hold it in the closed position and means for tilting the bucket.

9. In combination in a bucket, having an opening in its bottom, a plurality of doors mounted in said bottom, adapted when the bucket is in a vertical position to swing open when free to do so, one of said doors adapted when the bucket is moved to an inclined position to swing closed, and a connection between said doors to cause closing movement of one automatically to close the other.

10. In combination in a bucket, having an opening in its bottom, a plurality of doors mounted in said bottom, adapted when the bucket is in a vertical position to swing open when free to do so, one of said doors adapted when the bucket is moved to an inclined position to swing closed, and a connection between said doors to cause closing movement of one automatically to close the other, and a latch adapted automatically to move to engage a door and to hold it in the closed position.

11. In a bucket having an opening in its bottom, two movable members mounted in one position to close the bottom, the members being movably linked together, whereby movement of one is transmitted to the other, one of the movably mounted members adapted automatically and of itself to swing to a closed position, when the bucket is tilted, and thereby to move the other movably

mounted member to the closed position, and a toggle attached to each of said members and adapted when they are in the closed position to co-operate in holding them in that position and means for tilting the bucket.

12. In combination in a bucket having an open bottom and an open top, a fixed member partially closing the bottom, a pair of movably mounted doors mounted adjacent the bottom of the bucket, said doors adapted, when free to move and when the bucket is vertical, to swing open, one of them adapted when the bucket is tilted to swing to a closed position, the two doors being linked together, whereby movement of one to a closed position closes the other, and a toggle attached to the two doors and adapted when the doors are in the closed position to move to a fixed extended position to lock the doors closed, the toggle adapted when broken to free the doors for opening movement and means for tilting the bucket.

13. In combination in a bucket, having an opening in its bottom, a closure movably mounted to close said bottom, said closure positioned and proportioned to swing open when free to do so, and when the bucket is in one position, and positioned and proportioned automatically to swing closed when the bucket is moved to another position, and automatically operating latching means associated with said closure, adapted when the closure moves to the closing position to latch the same, to retain it in the closed position, said latch provided with a portion extending below the bottom of the bucket, whereby when the bucket is lowered upon a surface, the latch will contact said surface before the bucket and will be unlatched.

14. In combination in a bucket, having an opening in its bottom, a plurality of movable doors mounted to close said opening, said doors adapted, when free to move and when the bucket is in one position, to swing open and adapted when the bucket is in another position automatically to swing closed, and a toggle adapted, when said doors have moved to the closed position, to latch them in said position.

15. In combination in a bucket, having an opening in its bottom, a plurality of movable doors mounted to close said opening, said doors adapted, when free to move and when the bucket is in one position, to swing open and adapted when the bucket is in another position automatically to swing closed, and a toggle adapted automatically, when said doors have moved to the closed position, to latch them in said position.

16. In combination in a bucket, having an opening in its bottom, a plurality of doors mounted in said bottom, one of said doors adapted when the bucket is tilted to swing closed, and a connection between said doors to cause closing movement of one auto-

matically to close the other, and a toggle adapted automatically, as the door moves to the closed position, to move to lock the doors closed and means for tilting the bucket.

5 17. In combination in a bucket having an opening in its bottom, a movable door mounted to close said opening, said door adapted when free to move and when the bucket is in one position, to swing open, and adapted when the bucket is in another position automatically to swing closed.

10 18. In combination, a bucket having an open bottom, a plurality of doors pivoted therein and adapted to close the bottom, a motion transmitting connection interposed between the doors, a toggle link interposed between the doors when they are in the closed position to lock them and adapted when they are in the open position to float upward to permit them to swing open, means for suspending the bucket, means interposed in the path of the bucket for as it descends downwardly tilting it whereby the weight of one of the doors causes it to rotate downwardly from the open to the closed position so that the motion transmitting mechanism may open the other door upwardly to the closed position, the toggle being counterweighted so that as this happens, the toggle swings down to assist the door closing movement.

15 19. In combination, a bucket having an open bottom, a plurality of doors pivoted therein and adapted to close the bottom, a motion transmitting connection interposed between the doors, a toggle link interposed between the doors when they are in the closed position to lock them and adapted when they are in the open position to float upward to permit them to swing open, means for suspending the bucket, means interposed in the path of the bucket for as it descends downwardly tilting it whereby the weight of one of the doors causes it to rotate downwardly from the open to the closed position so that the motion transmitting mechanism may open the other door upwardly to the closed position, the toggle being counterweighted so that as this happens, the toggle swings down to assist the door closing movement, the guide means comprising an inclined member upon which the bucket travels and means associated with said member for guiding the bucket therealong.

20 55. Signed at Philadelphia, county of Philadelphia and State of Pennsylvania, this 17th day of April, 1931.

GEORGE L. MOREHEAD.
CHARLES M. YOUNG, JR.
